UNITED STATES PATENT OFFICE.

CHARLES A. HELM, OF CLEVELAND, OHIO.

FIRE-EXTINGUISHING APPARATUS.

Application filed March 10, 1926. Serial No. 93,660.

This invention relates to new and useful improvements in fire extinguishing apparatus or means.

One object of the invention is to provide an apparatus or means of the type indicated which will be capable of volatilizing a fire extinguishing liquid so as to generate a large volume of fire extinguishing gas rapidly and continuously during the progress of a fire and independently of the heat produced by the burning material.

Another object of my invention is to provide means of the character indicated especially designed to be used in conjunction with a machine or the like, which in its normal functioning produces a degree of heat sufficient to constitute a fire hazard, and having means for utilizing the heat generated by the machine for volatilizing the fire extinguishing liquid.

With these object in view and with the intention of providing for the securing of other advantages which will be described later my invention comprises the new and improved fire extinguishing means herein-after described in the specification, particularly pointed out in the claims, and illustrated in the accompanying drawings.

In carrying out my invention, I provide a volatilizing element, positive means for heating said element, means for supplying a volatile fire extinguishing fluid to the element, and means for discharging the gas generated by the volatilizing element.

In the accompanying drawings, wherein several ways of applying and carrying out my invention are illustrated, Fig. 1 is a side elevation of a moving picture machine with my invention applied thereto; Fig. 2 is a detail view in perspective on an enlarged scale of a portion of the picture machine showing the general arrangement of my device; Fig. 3 is a view in elevation of the volatilizing element; Fig. 4 is a section on line 4—4, Fig. 3; Fig. 5 shows a modified form of the volatilizing element; Fig. 6 is a section on line 6—6, Fig. 5.

Again referring to the drawings and particularly to Figs. 1, 2, 3 and 4, in which like numerals indicate the same parts, 10 represents the base of a moving picture machine, 11 the head of the machine, which carries the usual feeding mechanism (not shown) for the film and through which the film passes when being exposed. The film boxes for the rolls of film are indicated at 12,

and at 13 is indicated the lantern box which carries the customary projecting lamp, lenses and adjusting mechanism (not shown). The electric circuit is indicated at 14 and the controlling device therefor at 15 and 16. The film window is shown at 17, the shutter at 18 and the heat shield at 19, see Fig. 5.

When applying my fire extinguishing apparatus to a moving picture machine, it is preferable to remove the device known as the heat shield 19 which is mounted on the head of the machine between the lens and the film window, where the film is exposed to the light from the projecting lamp. As is well known, the object of the heat shield is to protect the parts of the head adjacent to the film window from the heat developed by the excess light rays from the projecting lamp. During the operation of the machine, the heat shield becomes highly heated due to the impinging of the excess light rays thereon.

After removing the heat shield 19 from the head 11, I substitute therefor my volatilizing element, which in the drawings is indicated by 20. When applying my volatilizing element to a moving picture machine, I prefer that it shall conform in its dimensions and configuration to those of the ordinary heat shield so that it may be readily substituted therefor.

The volatilizing element 20, therefore, in this instance comprises a thin rectangular shaped casting which is provided with a central aperture 21 for permitting the light rays to pass therethrough so as to impinge on the film. The casing or volatilizing element 20 is provided with a chamber 22. This chamber 22 is provided with an inlet opening 23 and one or more outlet openings 24.

On any suitable portion of the frame is mounted a closed container 26 for holding any suitable fire extinguishing liquid, preferably carbon-tetrachloride. The fire extinguishing liquid may be kept under a definite pressure either by the use of compressed air or other suitable means and the object of having the liquid under pressure is that it may flow freely from the container when desired. A suitable pipe or conduit 27 extends from the container 26 to the inlet opening 23 of the chamber 22 in the volatilizing element 20. The conduit 27 may comprise a heat insulating section 28 to prevent

the heat from the element 20 being conducted to the container 26.

The conduit 27 is provided with a suitable valve 29 which may be operated by means of a rod 30 so arranged that it may be readily grasped by the moving picture machine operator. A conduit 33 is connected with the outlet opening 24 and as shown extends direct through the wall of the head portion 11 of the picture machine, but this conduit may be branched and carried to as many portions of the machine as desired.

The operation of my fire extinguishing apparatus when applied to a moving picture machine is as follows.

A quantity of carbon tetrachloride is put in the container 26 and a definite pressure established on top of the liquid. After the machine has been in operation for a short time the walls of the chamber 22 of the volatilizing element 20 become highly heated. If the film takes fire, which is generally caused by some interruption in the feed of the film permitting a portion of the film to be unduly subjected to the action of the focussed rays of light, then the operator opens the valve 29 in the conduit 27 by manipulating the rod 30. The carbon tetrachloride liquid is forced down through the conduit 27 and enters the heated chamber 22. The liquid is immediately vaporized and escapes through the outlet 24 and the conduit 33 and enters the head 11. As the vaporizing surface of the chamber 22 is relatively large compared to the size of the outlet opening 24, considerable pressure is built up in the chamber 22 and the gas escapes from the conduit 33 with great force. The gas entering the head 11 drives the air away from the burning film and the carbon tetrachloride atmosphere established within the head 11 smothers out the fire. As the boxes 12 which hold the film rolls are in open communication with the head 11, the carbon tetrachloride gas will enter the film boxes and smother out any fire which may have communicated to the film rolls.

In Figs. 5 and 6 is shown a slightly modified form of the apparatus just described; 50 the modification consisting in using a section of tubing 20' for the vaporizing element. This tubing 20' is carried across the face of the regular heat shield in the path of the excess light rays. The heat shield is

indicated at A and the light aperture at B. 55

I do not desire to limit the scope of my invention to the embodiments herein described and shown in the drawings, as the invention may be carried out in many forms and applied in various ways. 60

What I claim is:—

1. In an apparatus of the character described, in combination with a moving picture machine, a volatilizing element arranged in the path of a portion of the light rays 65 from the projecting lamp so as to receive heat from said rays, means for supplying a volatile fire extinguishing medium to said element and means for directing the volatilized fire extinguishing medium in the path 70 of the film carried by said moving picture machine.

2. In an apparatus of the character described, in combination with a moving picture machine, a container arranged in the path of a portion of the light rays from the projecting lamp so as to receive heat from said rays, means for supplying a volatile fire extinguishing fluid to said container and means for directing the resultant gas from 80 said container into the path of the film carried by said moving picture machine. 75

3. In an apparatus of the character described, in combination with a moving picture machine, a volatilizing element arranged in the path of a portion of the light rays 85 from the projecting lamp so as to receive heat from said rays, said volatilizing element having an inlet and an outlet, means for feeding a volatile fire extinguishing fluid 90 to the inlet of said container under pressure and means for conducting the generated gas from said container to various parts of the moving picture machine, to extinguish fire in and around said machine. 95

4. In an apparatus of the character described, in combination with a moving picture machine, a volatilizing element arranged in the path of a portion of the light rays from the projection lamp so as to receive heat from said rays, means for feeding a volatile fire extinguishing fluid under pressure to said volatilizing element and means for directing the vaporized fluid in the path 100 of the film and into the film compartments. 105

In testimony whereof I affix my signature.

CHARLES A. HELM.
